US00D857779S

(12) **United States Design Patent** (10) Patent No.: **US D857,779 S**
(45) Date of Patent: **** Aug. 27, 2019**

(54) **CAMERA LENS**

(71) Applicant: **WHITEPOINT OPTICS OY**, Helsinki (FI)

(72) Inventor: **Arni Aromaa**, Helsinki (FI)

(**) Term: **15 Years**

(21) Appl. No.: **35/505,146**

(22) Filed: **May 7, 2018**

(80) **Hague Agreement Data**

Int. Filing Date: **May 7, 2018**

Int. Reg. No.: **DM/101505**

Int. Reg. Date: **May 7, 2018**

Int. Reg. Pub. Date: **Jun. 22, 2018**

(30) **Foreign Application Priority Data**

Apr. 6, 2018 (EM) 005216058-0001

(51) **LOC (12) Cl.** **16-05**

(52) **U.S. Cl.**

USPC **D16/219**

(58) **Field of Classification Search**

USPC D16/134, 136, 200, 213, 218, 219, 220,
D16/242, 245

CPC G02B 7/00; G02B 7/026; G02B 23/16;
G03B 7/00; G03B 17/02
